UNITED STATES PATENT OFFICE.

BENNO VOM EIGEN, OF NEWARK, NEW JERSEY, ASSIGNOR TO AUG.
GOERTZ & CO., OF NEWARK, NEW JERSEY, A FIRM.

BOX.

SPECIFICATION forming part of Letters Patent No. 761,461, dated May 31, 1904.

Original application filed October 30, 1903, Serial No. 179,147. Divided and this application filed January 11, 1904. Serial No. 188,458. (No model.)

To all whom it may concern:

Be it known that I, BENNO VOM EIGEN, a citizen of the United States, residing at Newark, in the county of Essex and State of New Jersey, have invented certain new and useful Improvements in Boxes; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

The present invention has reference to improvements in boxes; and the invention relates more particularly to improvements in that class of match-boxes which is carried in the pocket.

The present invention, which is a division of my former application for Letters Patent, filed October 30, 1903, Serial No. 179,147, has for its principal object to provide a novel and simple construction of holding - clasp and spring attachment for a box of the class above mentioned.

A further object of the present invention is to provide, with a match-box of this class, a means, preferably arranged in the cover or lid of the box, having removable scratching-pads which when they become useless with the constant scratching of the matches thereon can be replaced by other scratch-pads.

Other objects of the present invention not at this time more particularly mentioned will appear from the following detailed description of the same.

With the various objects of my present invention in view the same consists in the novel construction of match and other box hereinafter more fully set forth; and, furthermore, the invention consists in the various arrangements and combinations of parts, all of which will be described in detail in the following specification and then finally embodied in the clauses of the claim, which are appended to and form an essential part of the said specification.

The invention is clearly illustrated in the accompanying drawings, in which—

Figure 1 is a plan view of a match or other box made according to the principles of the present invention with the lid of the box represented in its open relation to the body of the box. Fig. 2 is a front edge view of the said box with the lid represented in its closed position upon the body of the box; and Fig. 3 is a longitudinal vertical section of the body of the box, the said section being taken on line 3 3 in Fig. 1 and looking in the direction of the arrow *a* in said figure to illustrate the general arrangement and construction of the spring-clasp of the box. Fig. 4 is a transverse vertical section of the box and lid in their closed relation, the said section being taken centrally across the body of the box and illustrating the spring-clasp in its holding engagement with a holding tongue or lug upon the lid. Fig. 5 is a horizontal section taken on line 5 5 in Fig. 2 of the drawings, illustrating the manner of attaching the spring-plate of the holding-catch to the body of the box and also one manner of securing a push-piece, knob, or finger-piece to the said spring-plate, the said parts being represented in their normal initial positions; and Fig. 6 is a similar view of the said parts, representing the said spring plate or bar in its actuated position. Fig. 7 is a detail cross-section taken on line 7 7 in said Fig. 5. Fig. 8 is a perspective view of the spring-catch in its detached position. Fig. 9 is a similar view of one of the fastening-rivets for securing the said spring-catch in its operative position upon the interior surface of the body of the box, and Fig. 10 is a perspective view of the knob or finger-piece to be used with the said spring-catch. Fig. 11 is a longitudinal vertical section, on an enlarged scale, of the lid or cover of the box and the removably-arranged scratch-pads, the said section being taken on line 11 11 in Fig. 1 of the drawings; and Fig. 12 is a perspective view of the said lid or cover with the scratch-pads removed, illustrating one means for detachably holding

the scratch-pads against the inner surface of the lid or cover of the box.

Similar characters of reference are employed in the above-described views to indicate corresponding parts.

Referring now to the said drawings, the reference character 1 indicates the complete match or other box, the same comprising a body 2 and a lid 3, both of which are made from sheet metal. The said body 2, as will be seen from the several figures of the drawings, is preferably of a rectangular configuration; but the general contour of the box is not essential, and the said body comprises a base 4 and its surrounding side portions, which form a front 5, a back 6, and the ends 7, all of which are preferably integrally united by being struck up or formed in any suitable manner from a suitable piece of metal. The said body 2 is preferably made in one or more or all of its side portions, as in the front, back, and ends, with an outwardly-extending portion 8 and an upper and inwardly extending portion 9, providing the said body with an upper edge 10, forming a bezel, and upon its interior with a depression or recessed portion 11, substantially as illustrated. The said outwardly-extending portion 8, formed in the front 5 of the body 2, is made with a suitably-disposed opening 12, in which is movably arranged a knob or finger-piece 13, preferably made as indicated in Fig. 10 of the drawings and being provided with a pair of lugs or prongs 14. The prongs are inserted through a pair of holes or perforations 16, formed in a spring plate or bar 15, which plate is made with an upwardly-extending and preferably inwardly inclining catch or holding member 17, provided with a receiving-opening 18. The said spring plate or bar 15 is also made with a pair of elongated openings 19 and is suitably secured in the recess or depression 11 in the inner face of the front 5 by means of suitable posts or rivets 20. Each rivet or post 20 is made with the rivet portion 21 and offsets or shouldered portions 22 and 23, the rivet portion 21 being arranged in suitably-disposed holes 24 in the front 5 and securely upset against the outer surface of the front 5, with the shoulders or offsets 22 resting against the inner face of the said front 5, while the portions 25 between the offsets are arranged in the elongated openings or holes 19 of the spring plate or bar 15 and the offsets 23 and the head portion 26 of each rivet or post being arranged outside of the spring plate or bar 15, as clearly illustrated in the several figures of the drawings. In this manner the said spring bar or plate 15 is operatively secured against the inner face of the front 5, with the end portions of said bar or plate slidably arranged upon the said posts or rivets 20, and the knob or finger-piece 13 extending from the opening 12 in the front 5. The slidable arrangement of the end

portions of the spring plate or bar 15 upon the posts or rivets 20 permits of the bowed relation of the said spring plate or bar (indicated in Fig. 6 of the drawings) when the knob or finger-piece 13 is forced in an inward direction to release the catch or holding member 17 of said spring plate or bar from its engagement with a holding lug or tongue 27, formed in the edge or projection 28 of the lid or cover 3 in the manner and for the purposes 75 to be presently described.

The back of the body 2 is made with a pair of upwardly-extending ears or curled hinge portions 29 and 30, and the lid or cover 3 is in like manner made at its rear edge with a pair of downwardly-extending ears or curled hinge portions 31 and 32, registering with the ears or curled hinge portions 29 and 30 in the manner represented in Fig. 1 of the drawings and the same being pivotally connected by 85 means of a suitable pintle in any usual manner.

Referring now to Figs. 1, 4, 11, and 12 of the drawings, it will be seen that I have provided the cover or lid 3 of the box with a pair of inwardly-extending members 33, having 90 the right-angled or bent edges 34 extending toward each other, the said members and their angular edges forming holding-guides and with the body portion 35 between the said members or parts 33 producing a suitable 95 holding means for slidably and removably retaining a number of scratch-pads 36 (for the scratching of the matches thereon) in place upon the inner face of the said lid or cover of the box. That the openings 37 formed in the said lid by the stamped-out members 33 may be covered the said lid is preferably made with a raised marginal or bead-like part 38, which surrounds a depression 39 in the outer face of the lid and in which I have arranged and suitably secured therein a face-plate or finish-plate 40, which may be suitably ornamented or may be provided with an advertisement, as may be desired.

From an inspection of Fig. 4 it will be seen that the holding catch or member 17 of the spring plate or bar 15 is arranged at an inclined angle to the upper edge of the said plate or bar 15 and that when the lid or cover 3 is being closed the holding lug or tongue 115 27 of said lid or cover will ride upon said member 17 and will spring into the opening 18 of said member 17, catching over the edge of the same to thereby retain the lid or cover in its closed position, as will be clearly evident.

From the previous description of my invention it will be seen that I have devised a simply-constructed box comprising but a very few parts which can be quickly and cheaply assembled. Furthermore, by providing the body of the box with the outwardly-extending portion 9 the use of a separate band or bezel, which has to be riveted or soldered in position, is clearly avoided, and a cheap and simple body construction is the result. It 130

will also be noted that by arranging the spring plate or bar 15 in the depression 11 these parts do not unnecessarily occupy the space for the matches or the like within the body 5 of the box; but it will be understood that this depression is not of itself an absolute necessity and that the spring plate or bar 15 may be arranged directly against the inner and flat face of the body of the box, in which 10 case the latter is provided with a bezel, secured therein in the usual manner.

By the arrangement of the holding means for the scratch-pad connected with the cover or lid of the box the box can be supplied 15 from time to time with a number of fresh scratch-pads when those previously placed in the box have become useless, and the box of itself when used as a match-box is not rendered useless for the want of a fresh scratch- 20 pad, especially when the box is to be used for carrying such safety-matches which can be ignited only on scratch-pads having specially-prepared scratching-surfaces.

I am aware that some changes may be made 25 in the several arrangements and combinations of the parts without departing from the scope of this invention. Hence I do not limit my invention to the exact arrangements and combinations of the parts as described in the foregoing specification and as illustrated in the accompanying drawings; nor do I confine myself to the exact details of the construction of the said parts.

Having thus described my invention, what 30 I claim is—

1. In a box, the combination, with the body of the box provided with side portions and an opening in one of said side portions, of a spring-plate arranged against the inner face 40 of one of said side portions of said body, a finger-piece on said spring-plate extending into said opening, and means connected with the said side portion of the said body of the box with which the end portions of the spring-plate are slidably connected that the spring-plate may be bowed when the finger-piece is depressed, substantially as and for the purposes set forth.

2. In a box, the combination, with the body 50 of the box provided with side portions and an opening in one of said side portions, of a spring-plate arranged against the inner face of one of the side portions of said body, the said spring-plate being provided near its end portions with elongated openings, a finger-piece on said spring-plate extending into the said opening in the body of the box, and fastening devices by means of which the end portions of said spring-plate are slidably connected with said side portion of said body of the box, each fastening device, consisting, essentially, of a rivet portion secured to said side portion, offsets 22 and 23 and a portion 55 25, said portion 25 being arranged in the elongated opening of said spring-plate, and a

head portion 26 on each fastening device, substantially as and for the purposes set forth.

3. In a box, the combination, with the body of the box provided with side portions having a recessed portion 11, and provided with an 70 opening in one of said side portions, of a spring-plate arranged in said recessed portion 11, a finger-piece on said spring-plate extending into the said opening, and means connected with the said side portion of the said body of the box with which the end portions of the spring-plate are slidably connected that the said spring-plate may be bowed when the finger-piece is depressed, substantially as and for the purposes set forth.

4. In a box, the combination, with the body of the box provided with side portions having a recessed portion 11, and provided with an 80 opening in one of said side portions, of a spring-plate arranged in said recessed portion 85 11, the said spring-plate being provided near its end portion with elongated openings, a finger-piece on said spring-plate extending into the said opening in the body of the box, and fastening devices by means of which the 90 end portions of said spring-plate are slidably connected with the side portion of the said body of the box, each fastening device consisting, essentially, of a rivet portion secured to said side portion, offsets 22 and 23 and a 95 portion 25, said portion 25 being arranged in the elongated opening of said spring-plate, and a head portion 26 on each fastening device, substantially as and for the purposes set forth.

5. In a box, the combination, with the body of the box provided with side portions and an opening in one of said side portions, and a hinged lid, of a spring-plate arranged against the inner face of one of the said side portions 100 105 of said body, a finger-piece on said spring-plate extending into the said opening, means connected with the said side portion of the said body of the box with which the said end portions of the spring-plate are slidably connected that the said spring-plate may be bowed when the finger-piece is depressed, an upwardly-extending and inwardly-inclining holding member 17 connected with said spring-plate, an edge or projection 28 on said lid, 110 115 and a holding-lug connected with said edge or projection normally in holding engagement with said holding member 17, substantially as and for the purposes set forth.

6. In a box, the combination, with the body 120 of the box provided with side portions having a recessed portion 11 and provided with an opening in one of said side portions, and a hinged lid, of a spring-plate arranged in said recessed portion 11, a finger-piece on said 125 spring-plate extending into the said opening, means connected with the said side portion of the body of the box with which the end portions of the spring-plate are slidably connected that the said spring-plate may be bowed when 130

the finger-piece is depressed, an upwardly-extending and inwardly-inclining holding member 17 connected with said spring-plate, an edge or projection 28 on said lid, and a holding-lug connected with said edge or projection normally in holding engagement with said holding member 17, substantially as and for the purposes set forth.

7. A box comprising a body and a hinged lid, the said body having side portions provided with outwardly-extending portions 8 and inwardly-extending portions 9 to provide a $\square$ -shaped depression 11 within the box, and a surrounding edge 10, all integrally formed with the said body, said edge 10 providing a bezel over which the edge of the lid can be arranged, substantially as and for the purposes set forth.

8. In a match-box, the combination, with a body and a hinged lid, of a scratch-pad, a pair of holding-guides struck up from the inner face of said lid beneath which the said scratch-pad is slidably arranged and is removable from said box, the said lid being provided in its outer face with a depression and a raised marginal edge surrounding said depression, and a face-plate secured in said depression, substantially as and for the purposes set forth.

In testimony that I claim the invention set forth above I have hereunto set my hand this 8th day of January, 1904.

BENNO VOM EIGEN.
